 Steglitz, Germany

Application December 17, 1934, Serial No. 757,773
 In Germany December 20, 1933

3 Claims. (Cl. 179—171)

The invention relates to the problem of the effective amplification of a wide frequency band, such as occurs in the case of television low-frequency amplification or television intermediate frequency amplification. It is known that for these purposes comparatively low-ohmic anode resistances require to be employed, (for example, $R_a=5000$ ohms and less for images of approximately 50,000 image points and more).
 10 The amplification per tube (constituted by the equation $V=S.R_a$) may, therefore, only be increased by the use of tubes with improved steepness S.

The subject matter of the invention is the introduction of an aperiodic reaction coupling, for example a feed-back or reflex connection with the aid of galvanic coupling of a feed-back-condenser, over every two tubes, and more particularly the use of a connection system of this 20 nature specifically for television purposes.

The invention is described in conjunction with the appended drawing which shows diagrammatically an exemplary embodiment of the invention. There are shown in the drawing two 25 tubes of an intermediate carrier-wave amplifier. The tubes form part of a superheterodyne receiver, which picks up the transmission on an ultra-short wave (7 metres), then passes the same by means of a connection system known 30 per se to an intermediate wave of approximately 150 metres, and after amplification rectifies this intermediate wave. The said intermediate wave is surrounded by side bands up to the extreme 35 wave of 100 and 300 metres. This frequency band requires to be amplified as evenly and effectively as possible. An amplifier of ordinary construction should possess for this purpose not more than 4000 ohms as anode resistance 1, whilst for avoiding of the undesired amplification 40 of waves longer than the intermediate waves, the grid resistance 2 should be a comparatively low resistance, for example 10,000 ohms, and the condenser 3 should be approximately $5.5 \cdot 10^{-5} mF$. The amplification thus capable of 45 being obtained is in the case of ordinary tubes with a working steepness of 2-3 milliamperes per volt merely approximately 8-12 per stage. In order to have an improvement in the amplification there is used a reaction circuit arrangement 50 in combination with an impedance producing a defined resonance circuit arrangement in the anode circuit of that tube from which reaction is derived.

This impedance which is used additionally in 55 accordance with the invention, consists of a coil

7 (see drawing), which produces with its self-capacity 8 indicated in broken lines a defined resonance effect. This coil 7 which may be damped as desired by means of a parallel resistance 9 is connected between the anode resistance 5 of the valve from which reaction is derived and the positive terminal of the anode supply source, the negative terminal of which is earthed.

The feed-back connection is performed by a variable condenser 11 which is lying in the line 10 10 connecting the grid of the preceding valve with the connection point of the anode resistance 5 and the parallel connection network 7, 8, 9. By means of this resonant circuit arrangement a preferred reaction coupling of those frequency 15 bands which are selective as desired may be effected and correspondingly by adjusting a defined resonance effect an improvement in the amplification of the whole circuit arrangement is effected. The variable condenser 11 is chosen 20 to have a maximum capacity of $5.5 \cdot 10^{-5} F$. The amplification is then improved only in respect of frequencies in the vicinity of the natural frequency of the structure 7, 8, 9. Low frequencies, in very desirable fashion, are affected adversely 25 as compared with these higher frequencies. This effect is very desirable in the case of carrier-wave amplification, as the same offers the advantage of reduced liability to interference in comparison with simple full aperiodic resistance 30 amplifiers.

Naturally in place of the stated coupling impedances 7, 8 it is also possible to employ as desired other coupling impedances composed of resistances, condensers and coils for back-coupling purposes, and accordingly a desired improvement in the amplification may be adjusted in respect of a frequency band selected as desired. The optimum frequency of the resistance amplifier to which the reflection is to be 40 applied is disposed to coincide with the natural frequency of said impedance. The resistance amplifier per se amplifies without distortion only in respect of that frequency which is best amplified, i. e. for which the amplifier is dimensioned 45 so that back-couplings may be readily produced only for the range of this frequency, and on the other hand even weak reaction couplings are sufficient for obtaining large improvements, so that the danger of self-excitation in 50 this coincidence of the natural frequency curve with the frequency curve of the feed-back coupling according to the invention is reduced to a minimum.

The coupling may also be taken more particu- 55

larly whilst omitting intermediate stages over the first and fourth stages, or when employing semi-aperiodic transformer couplings as described for example in detail in the application Ser. No. 5 749,511 over an odd number of stages, as the transformer coupling permits of phase-reversal by simple change of polarity and thus dispenses with the intermediate tube.

I claim:

- 10 1. In a television amplifier system a regenerative intermediate carrier frequency amplifier, included in a super-heterodyne receiver, for amplifying wide television frequency bands, comprising a plurality of amplifier stages, coupled with each other by resistance capacity coupling means, means in said amplifier forming a feed-back connection between said amplifier stages in aperiodic fashion, i. e., aperiodic for said large frequency band to be amplified, said feed-back connection means consisting of a variable condenser in combination with an impedance producing a defined resonance effect with its self-capacity and being damped by a parallel resistance, said means being dependent on the frequency to be amplified.
- 15 2. In a television amplifier system a regenerative intermediate carrier frequency amplifier, included in a super-heterodyne receiver, for amplifying wide television frequency bands, comprising a plurality of amplifier stages, coupled with each other by resistance capacity coupling means, means in said amplifier forming a feed-back connection between said amplifier stages in galvanic aperiodic fashion, i. e., aperiodic for said large frequency band to be amplified, said feed-back connection means consisting of a self-induction in the anode circuit of an amplifier valve, a damping resistance connected in parallel to said self-induction, said parallel connection

net-work being connected between the anode resistance of said valve and the positive terminal of the anode supply source, the negative terminal of which is earthed, and a variable condenser, the one electrode of said condenser being connected between the connection point of said anode resistance and said parallel connection net-work, and the other electrode of said condenser being connected to the grid of the preceding valve.

10 3. In a television amplifier system a regenerative intermediate carrier frequency amplifier, included in a super-heterodyne receiver, for amplifying wide television frequency bands, comprising a plurality of amplifier stages, coupled with each other by resistance capacity coupling means, means in said amplifier forming a feed-back connection between said amplifier stages in galvanic aperiodic fashion, i. e., aperiodic for said large frequency band to be amplified, said feed-back connection means consisting of a self-induction in the anode circuit of an amplifier valve, a damping resistance connected in parallel to said self-induction, said parallel connection net-work being connected between the anode resistance of said valve and the positive terminal of the anode supply source, the negative terminal of which is earthed, and a variable condenser, the one electrode of said condenser being connected between the connection point of said anode resistance and said parallel connection network, and the other electrode of said condenser being connected to the grid of the preceding valve, the natural frequency of said self induction coinciding with the optimum frequency 25 amplified by said amplifier without phase distortion.
